UNITED STATES PATENT OFFICE.

JAMES W. MCNEIL, OF NEWARK, NEW JERSEY.

SHEET-METAL BARREL.

1,394,923.

Specification of Letters Patent. Patented Oct. 25, 1921.

Application filed June 4, 1920. Serial No. 386,554.

To all whom it may concern:

Be it known that I, JAMES W. MCNEIL, a subject of the King of Great Britain, and resident of Newark, in the county of Essex 5 and State of New Jersey, have invented certain new and useful Improvements in Sheet-Metal Barrels, of which the following is a specification.

This invention has relation to that type of 10 barrel represented by my former Patent No. 1,262,222, dated April 9, 1918, in which the body of the barrel is made of a single sheet of metal provided with inwardly-extending integral ribs at spaced intervals, these ribs 15 running from head to head of the barrel and increasing in depth toward each head. The objection to this type of barrel is that the increase in the width of the ribs toward the ends of the barrel not only unduly obstructs 20 the interior of the reduced ends of the barrel, but materially reduces the capacity of the barrel, particularly when used as a container for bulky articles. It is one of the 25 objects of this invention to avoid this objection by so cutting the blank that when curled into bilged-barrel form the interior of the ribs may be made of uniform length throughout, as more fully hereinafter set forth.

30 A further object of the invention is to provide improved means for removably locking the heads within the chime portions of the barrel-body, this locking means being so constructed that the heads are not only 35 locked in place without the use of extraneous fastening devices but may be repeatedly removed and reinserted without materially injuring either the heads or the chime portions of the barrel, as more fully hereinafter set forth.

In the accompanying drawings:

Figure 1 is a side elevation of a barrel embodying the invention;

Fig. 2 a plan view thereof;

Fig. 3 a fragmentary vertical section taken along one of the lines of fold defining the "staves" between the abutting faces of the double-walled rib-like reinforcement;

Fig. 4 a vertical section taken between two 50 adjacent ribs;

Fig. 5 a fragmentary plan view of the blank from which the body is formed;

Fig. 5^a a fragmentary plan view of a slightly modified form of blank;

Fig. 6 a perspective view of one of the 55 barrel heads;

Figs. 7, 8 and 9 similar fragmentary sectional views showing a part of the chime at one end of the body and the manner of assembling the head and end hoop on the 60 chime;

Figs. 10 and 11 detail horizontal sections taken respectively through the divided and integral portions of the internal rib-like reinforcements of the body; and

Fig. 12 a detail view showing adjacent 65 divided and integral portions of one of the reinforcing ribs.

The barrel body is preferably formed from a single blank 1 of sheet steel or other 70 suitable metal having portions thereof along opposite edges of the blank cut away, as shown in Fig. 5, to produce chime-forming portions 2. In order to give the body the external appearance of a barrel formed of 75 independent staves and to produce internal rib-like reinforcements, the blank is folded in one direction along straight lines of fold 3 and in the opposite direction along curved lines of fold 4 and 5 at opposite sides of each 80 line 3. The lines 4 and 5, as shown in Fig. 5, are spaced equal distances from line 3 midway the notched edges of the blank and gradually recede from line 3 and from each other toward the notched edges of the blank 85 to points coincident with the inner ends of the side edges of the chime portions 2.

The excess metal between each two adjacent lines of fold 4 and 5 forms an integral 90 stave-connecting web which increases in width toward each notched edge of the blank, and it will be obvious that if the lines of fold 3 extended from end to end of these webs, the webs would form ribs increasing in 95 depth toward each end of the barrel when the blank was folded. Such ribs would unduly obstruct the interior of the reduced ends of the barrel and would materially reduce the capacity of the barrel, particularly

for use as a container for bulky articles. 100 Barrels so formed would also be weaker in the middle than at the ends. To avoid these objections, I prefer to stamp the blank 1 before folding as shown in Fig. 5, namely by cutting the metal between lines 4 and 5 along a staggered or zig-zag line 6 inwardly from each notched edge of the blank for approximately one-fourth the distance between the

edges of the blank. These lines of cut terminate at the outer ends of the lines of fold 3 and criss-cross back and forth across the longitudinal center of the stave-connecting webs, or in other words, across prolongations of the lines 3, so as to form when the blank is folded pairs of abutting flanges or divided rib walls 7. The flanges 7 form extensions of the two walls of the integral double-walled ribs 8 formed by folding the undivided portions of the excess metal along lines 3, 4 and 5. It will be observed that the transversely extending portions of the lines of cut 6 decrease in length toward the inner ends of the lines 6 and thus form a plurality of staggered tongues or lugs 9 on the flanges 7 of gradually decreasing length toward the inner ends of said flanges. It will be observed also that by thus forming cuts 6 two lines from the end of line 3, each touching the bases of the tongues 9 on one flange, will be parallel with lines 4 and 5, respectively, so that the body portions of the flanges are of uniform depth from end to end and also the same depth as the walls of ribs 8, so that the integral and split portions of the rib-like reinforcements are of uniform depth from one chime to the other of the completed barrel body.

30 After the body blank is folded along lines 3, 4 and 5 to produce a bilged body, the meeting ends of the blank are welded or otherwise secured together and the lugs 9 on each flange 7 are bent around the inner edge of the adjacent flange to securely lock the flanges together. In stamping out the notches to form the chime portions 2, I also cut away the adjacent end edges of body portions of the flanges 7 so that the outer end edges of the rib-like reinforcements will form inclined head-supporting shoulders or abutments, as more clearly shown in Figs. 7, 8 and 9. The two heads are of similar construction and are secured in place in the same manner. Each head is stamped or otherwise formed from sheet metal and comprises a disk-like body 10 having an up-standing annular flange 11 at its outer edge, which flange is pressed inwardly at 12 to form an outwardly facing circumferential channel. The chime-forming portions 2 of the blank are bent outwardly along the lines 13 so that they will form a continuous annular chime concentric with the longitudinal axis of the barrel when the body blank is folded as above described and the cupped heads are inserted in the chimes thus formed. The disk-like bodies 10 of the heads are indented at intervals around flanges 11 by means of a suitable beveled tool or chisel to form indentations 14 having inclined walls seated against the inclined ends of the flanges 7. A pair of metallic end hoops 15 embrace the chimes and have flaring portions which lie against the bilged surface

of the barrel body and are welded thereto. The heads are interlocked with the chime portions 2 by indenting hoops 15 and the chime portions with a suitable chisel or punch at intervals as shown at 16, thereby forcing a part of the metal of the chime portions into channel 12 on the head flange. The heads may be removed by hammering the inner wall of channel 12 opposite the indentations 16 to flatten out the interlocked portions of flange 11, chime 2 and hoop 15. A pair of hoops 17 are welded to the exterior of the barrel body, said hoops being preferably located so as to span the points of junction of the inner ends of the flanges 7 or split rib portions with the outer ends of the undivided rib portions 8.

It will be obvious that a barrel having a more accentuated bilge than that shown in Fig. 1 may be produced without increasing the depth of the ribbed reinforcements by increasing the curvature of the lines of fold 4 and 5 and removing all metal between the end portions of each two lines 4 and 5 from the ends of lines 3 to the adjacent edges of the blank 1 not required to form the flanges 7 and tongues 9, as shown for example in Fig. 5^a. The tongues 9 on flanges 7 of such a barrel may be formed of uniform length, preferably approximating the width of the body portions of flanges 7 which are substantially the same width from end to end as the distance between line 3 and lines 4 and 5 at the central portion of the barrel body, as shown in Fig. 5^a. While the chime portions 2, tongues 9 and flanges 7 of this modified form of barrel may be formed, and the necessary amount of surplus metal be removed, in various ways, I prefer to form the parts 2, 7 and 9 and remove the surplus metal at a single operation. This may be done by stamping out irregularly shaped portions of the blank 1 at intervals along opposite side edges thereof, one edge of each of which portions is defined by the edge of the blank, and the remaining two edges of which are irregular and converge at the end of the adjacent line of fold 3, as shown in Fig. 5^a.

What I claim is:

1. A sheet metal barrel comprising a bilged body having smooth non-ribbed chimes split longitudinally of the barrel at intervals and longitudinally extending double-walled ribs between the chimes projecting radially into the interior of the body and terminating at the inner ends of the lines of division in the split chimes, the walls of each rib being of uniform width from end to end and being divided along their inner edges at each end of the rib and integral with each other along the inner edge of the central portion of the rib, the inner edges of the abutting divided portions of the walls of each rib being provided with

relatively staggered tongues and the tongues on each wall being bent laterally around the abutting wall.

2. A barrel having a bilged body formed of sheet metal and provided with double-walled internal ribs of uniform width from end to end extending longitudinally of the body, the walls of each rib being integral with the body from end to end along their outer edges and divided along their inner edges at each end throughout a portion of the length of the rib, the divided wall portions at each end of each rib being provided with interlocking parts holding the same against relative movement, and the body being provided with smooth cylindrical chimes at its ends each formed of a plurality of tongues having abutting longitudinal edges terminating at the adjacent ends of the outer edges of the divided portions of the walls of the ribs.

3. A barrel having a bilged body provided with double-walled internal ribs of uniform width from end to end extending longitudinally of the body, the outer edges of the walls of each rib being unconnected with each other and integral with the body from end to end of the rib, the walls of each rib being divided along their inner edges at each end of the rib and integral with each other along the central portion of the inner edge of the rib, the adjacent walls of each divided end portion of the ribs being provided with relatively staggered integral tongues at their inner edges, the tongues on each wall being bent laterally around the abutting wall and decreasing in length toward the inner ends of the divided portion of the rib, said body being formed of a single piece of sheet metal and said tongues being formed of the metal in said piece of material in excess of that required to produce a bilged body with ribs of uniform width from end to end, the tongues on each two abutting rib walls being spaced apart distances equal to the width of the tongues.

4. A metal barrel having a bilged body formed with smooth cylindrical chimes split longitudinally of the body at intervals, the body being provided with a plurality of double-walled internal ribs extending longitudinally of the body from the inner edge of one chime to the inner edge of the other chime and of uniform width from end to end, the two walls of each rib being integral with the body from end to end along their outer edges and being divided along the inner edge of the rib at each end from the chimes to points intermediate the chimes and the middle of the barrel body, the abutting divided wall portions being provided with relatively staggered tongues, the tongues on each wall portion being spaced apart distances equaling the width of the tongues and being bent around the inner

edge of the abutting rib wall against the outer side of the abutting wall, said ribbed body and split chimes being formed of a single piece of sheet metal.

5. A metal barrel having a bilged body formed with smooth cylindrical chimes split longitudinally of the body at intervals, the body being provided with a plurality of double-walled internal ribs extending longitudinally of the body from the inner edge of one chime to the inner edge of the other chime and of uniform width from end to end, the two walls of each rib being integral with the body from end to end along their outer edges and being divided along the inner edge of the rib at each end from the chimes to points intermediate the chimes and the middle of the barrel body, the abutting divided wall portions being provided with relatively staggered tongues, the tongues on each wall portion being spaced apart distances equaling the width of the tongues and being bent around the inner edge of the abutting rib wall against the outer side of the abutting wall, a one-piece cup-shaped sheet metal head seated within each of the chimes, and sheet metal hoops surrounding the chimes, the annular side walls of the heads each being formed with an outwardly facing circumferential channel and the chime hoops and chimes having portions thereof pressed inwardly into said channel.

6. A barrel having a bilged body formed of sheet metal and provided with chimes formed by bringing together the side edges of spaced tongues on the ends of the blank, the body of the blank between the tongues being divided longitudinally a portion of its length at each end and the portions of the body between each two tongues being folded along three parallel lines to provide double-walled internal ribs extending between the chimes and projecting radially into the barrel a uniform distance from end to end of the ribs, the outer edges of the walls of each rib being integral with the body from end to end and the inner edges of said walls being integral with each other along the central portion only of the rib, the inner edges of the divided wall portions at each end of the rib being provided with integral relatively staggered tongues formed of excess metal in the end portions of the blank with the bases of the tongues parallel with the lines on which the respective rib walls are folded inwardly, the tongues on each wall being bent around the inner edge of the abutting wall.

7. A sheet-metal barrel having an annular sheet-metal chime-portion, a head fitting within the chime-portion and provided with an annular inwardly-extending channel, a hoop-band fitted around the exterior of the chime-portion and indentations formed in

the hoop and the chime-portion and extending into said channel, whereby, by flattening the channel coincident with each indentation to thereby flatten the indentations also, the head may be removed.

8. A sheet-metal barrel having annular chime-portions and interior ribs terminating at the bases of said chime portions and having their ends inclining downwardly and inwardly, sheet-metal heads fitting within the chime portions and having an inward indentation coincident with each rib, the inner wall of each indentation fitting against the inwardly and downwardly-inclined end of one of the ribs, and means for locking the heads in place.

9. A sheet-metal barrel comprising a

bilged body having chimes split longitudinally of the body at intervals, portions of the body being folded to provide longitudinally-extending double-walled ribs between the chimes, projecting radially inwardly from the body-wall, the inner edges of the walls of said ribs being substantially parallel with the bilged body from end to end, and said inner edges of the walls of each rib being integral along the central portion of the rib and divided from each other throughout the remaining end-portions of the rib, means being provided for clamping together the aforesaid divided walls of the ribs.

In testimony whereof I hereunto affix my signature.

JAMES W. McNEIL.
